UNITED STATES PATENT OFFICE

JOSEPH C. LEWIS, OF CANTON, OHIO, ASSIGNOR TO CHARLES W. KEPLINGER, RECEIVER OF THE AMERICAN ELECTRIC SWITCH CORPORATION, OF MINERVA, OHIO, A CORPORATION OF DELAWARE

ENTRANCE SWITCH AND SERVICE BOX

Application filed July 18, 1925. Serial No. 44,609.

This invention relates to improvements in entrance or service box construction such as is used at the entrance of an electric line into a building, and more particularly to the construction of the entrance switch which is located within the box and to the co-operation of the switch with the box whereby, regardless of the position of the switch, access cannot be had to the inside of the box, and whereby the switch may be knocked down to permit the same to be folded entirely within the box for the purpose of shipping.

An embodiment of the invention is illustrated in the accompanying drawings, in which,

Figure 1 is a fragmentary sectional view of a switch box showing the switch in open position;

Fig. 2, a similar view showing the switch in closed position;

Fig. 3, a detail perspective view of the link which connects the switch handle to the switch blade;

Fig. 4, a view similar to Figs. 1 and 2 showing the switch folded within the box for shipping;

Fig. 5, a section taken as on the line 5—5, Fig. 2; and

Fig. 6, a section through the switch box showing the pivoted latch bar in folded position for shipping.

Similar numerals refer to similar parts throughout the drawings.

The box 1 may be formed of sheet metal of a size to accommodate the switch block 2 and one or more fuse blocks. Each of these blocks is formed of suitable insulation material which may be connected to the bottom of the box 1 as by screws 5 or the like.

40 A line wire may be connected with the contact jaw 11 of the switch, and the blade 15 is pivotally connected as at 16 to the bracket 17, which may be electrically connected with one or more fuses in the switch box.

45 A plurality of binding posts 28 corresponding to the number of circuits to be wired from the box, are mounted in spaced relation upon the insulating box 2 and wires may be led from each of the binding posts to one side 50 of each circuit, and the binding posts may

be electrically connected as by a suitable bus bar with a line wire. The other side of each house circuit may be led through the usual meter and back to the necessary fuses housed within the switch box.

55 A bifurcated upright 31 is mounted upon the bottom of the box adjacent to the switch block 2, and the switch handle 32, which is of insulation material, is pivoted thereto as by a pin 33.

60 This handle has the grooved arcuate shoulders 34 upon each side to receive the depending curved flanges 35 formed at the sides of the slot 36 in the hinged lid 37 of the entrance box.

65 The reduced peripheral portion 36^a of the switch handle extends through the slot 36 and is provided with a stem 32^a for manually operating the same. The inner side of the handle 32 is recessed as at 38, one end of the 70 L shaped link 39 being pivotally connected therein as by the pin 40.

75 The link 39 may be formed of a single sheet of metal bent upon itself as at 41, the opposite end of said link being pivotally connected to the switch blade 15 as by the pin 42, the folded portion 41 of the link forming a stop to limit the opening movement of the switch blade, as shown in Fig. 1, and the inner edge 43 of the handle contacting 80 with the adjacent edge of the link when the blade is in closed position, as shown in Fig. 2, thus relieving the link and switch blade from strain.

85 As shown in Figs. 1, 2 and 5, the arcuate outer edge portion 36^a of the handle entirely closes the slot 36 in the door at all times, thus preventing access to the interior of the box through this slot.

90 When it is desired to pack the box for shipping, in order to economize space, the pivot pin 33 of the switch handle is removed and the handle folded into the position shown in Fig. 4, into the bifurcated bracket 31, and the pin 33 replaced in the aperture provided 95 therefor in the handle.

99 The latch bar 45 for the lid 37 is pivoted at its lower end as at 46 to an adjacent side wall of the box, the apertured upper end thereof being adapted to extend through a 100

slot in the lid 37 when the box is in locked position. When it is desired to pack the box for shipping this latch bar is swung downward upon its pivot to permit the lid 37 to be closed as shown in Fig. 6.

5 The pivoted switch blade, pivoted operating handle, and connecting link disclosed and described but not claimed herein has been made the subject matter of my copending application for entrance switches filed May 2, 10 1927, Serial No. 188,169, which is a division of this application. The service box lid and latch bar disclosed, described but not claimed herein has been made the subject matter of 15 my copending application for latches for service boxes, filed May 2, 1927, Serial No. 188,170, which is a division of this application.

I claim:

20 1. A box provided with a slot having in-turned flanges at its side edges, a switch blade within the box, and an operating handle positively connected with the blade having a grooved portion for engagement with 25 said flanges.

2. A box provided with a slot having in-turned flanges at its side edges, a switch blade within the box, and an operating handle positively connected with the blade having a 30 shouldered grooved portion for engagement with said flanges.

3. A box provided with a slot having in-turned flanges at its side edges, a switch blade within the box, and an operating handle positively connected with the blade having a 35 shouldered arcuate grooved portion for engagement with said flanges.

In testimony that I claim the above, I have hereunto subscribed my name.

40
